UNITED STATES PATENT OFFICE

156,536

TOOL HANDLE

Hy A. Keidan, Detroit, Mich.

Application May 24, 1947, Serial No. 139,262

Term of patent 3½ years

(Cl. D93—4)

To all whom it may concern:

Be it known that I, Hy A. Keidan, a citizen of the United States, residing at Detroit, in the county of Wayne and State of Michigan, have invented a new, original, and ornamental Design for Tool Handles, of which the following is a specification, reference being had to the accompanying drawings, forming part thereof.

Figure 1 is a perspective view of a tool handle, showing my new design;

Figure 2 is a side elevation;

Figure 3 is an elevation of the tool-receiving end, and

Figure 4 is a view of the other end.

I claim:

The ornamental design for a tool handle, as shown.

HY A. KEIDAN.
